United States Patent Office

Des. 228,323

Patented Sept. 11, 1973

228,323

CRASH HELMET

Richard P. MacCoon, Los Angeles, Calif., assignor to
Royal Industries, Inc., Pasadena, Calif.

Filed Aug. 12, 1971, Ser. No. 171,418

Term of patent 14 years

Int. Cl. D2—03

U.S. Cl. D2—232

FIG. 1 is a perspective view of a crash helmet showing my new design;

FIG. 2 is a rear view thereof on a reduced scale and with the face shield in a lowered position;

FIG. 3 is a side view thereof;

FIG. 4 is a front view;

FIG. 5 is a view of the other side;

FIG. 6 is a bottom view; and

FIG. 7 is a top view.

I claim:

The ornamental design for a crash helmet, as shown.
